UNITED STATES PATENT OFFICE.

CLARENCE G. HILLIGAS, OF CADIZ, AND FRANK E. HILLIGAS, OF HARRISVILLE, OHIO.

HEADLIGHT-STEERING MECHANISM.

1,174,148.

Specification of Letters Patent.

Patented Mar. 7, 1916.

Application filed January 27, 1915. Serial No. 4,732.

To all whom it may concern:

Be it known that we, CLARENCE G. HILLIGAS and FRANK E. HILLIGAS, citizens of the United States, residing at Cadiz, in the county of Harrison, and at Harrisville, in the county of Jefferson, respectively, and State of Ohio, have invented certain new and useful Improvements in Headlight-Steering Mechanism, of which the following is a specification.

This invention relates to an improved automobile headlight steering mechanism and has as its primary object to provide a mechanism of this character having as its salient feature, simplicity of construction and which may be readily applied to automobiles of conventional type without the necessity of structural change therein.

The invention has as a further object to provide an improved mechanism of this character adapted to be operatively connected to the connecting rod of the steering mechanism of the vehicle so that reciprocation of the said rod will effect a corresponding turning movement of the lamps to thus direct the rays of the lamps in the path of the machine as the machine is guided.

A further object of the invention in this connection is to provide a construction wherein the lamp brackets employed will be freely connected with the body of the machine and wherein a connection will be interposed between the connecting rod and the said brackets having slideable connection both with the connecting rod and with the lamp receiving brackets to permit of the free vertical movement of the brackets with the body under the influence of the springs of the machine and to compensate for the shifting of the connecting rod relative to the brackets.

The invention has as a still further object to provide an improved construction wherein in the lamp receiving brackets will be yieldably held seated in operative position upon the body of the machine so that vertical movement of the body under the influence of the springs of the machine will not affect the independent vertical movement of the said brackets.

Other and incidental objects will appear as the description proceeds and in the drawings wherein we have illustrated the preferred embodiment of the invention and wherein similar reference characters designate corresponding parts throughout the

several views, Figure 1 is a front elevation, partly broken away, showing our improved device applied to an automobile of conventional type, Fig. 2 is a side elevation, more particularly illustrating the mounting of the lamp receiving brackets and the connection therebetween and the connecting rod of the machine, the machine being partly broken away and portions thereof being shown in section, Fig. 3 is a fragmentary plan view particularly illustrating the operation of the connection between the lamp brackets and the connecting rod of the machine, Fig. 4 is a perspective view showing the mechanism detached, and Fig. 5 is a fragmentary sectional view more particularly illustrating the detail construction of the device.

Referring now more particularly to the drawings, we have, for convenience, illustrated a lamp bracket and associated mechanism in connection with a conventional type of automobile, employing at the front end thereof, bracket arms 10 for operatively supporting the forward extremities of the fenders and including as a part of the steering mechanism of the automobile, a conventional type of connecting rod 11. While we have illustrated but one lamp bracket and the means for connecting the said bracket to the rod 11, still, it is to be understood that one of the brackets and the associated mechanism is to be employed at each side of the machine to operatively receive a pair of headlights in the usual manner and since the construction of each of said brackets and associated mechanism is identical, only one will be described.

It will be noted that the bracket arm 10 is secured at one extremity to the body of the machine beneath the hood 12 thereof and at the forward extremity of the hood, while the opposite extremity of the said arm is arranged to support the adjacent free extremity of the fender 13. Intermediate its ends, and adjacent the inner terminal thereof, the rod 11 is longitudinally bent to provide a horizontally disposed portion which is laterally enlarged to form a seat 14, said seat being formed centrally with a vertically extending bore.

Coming now more particularly to the subject of the present invention, we employ a lamp receiving bracket 15 which includes a shank or stem 16 providing at its upper extremity, spaced vertically extending arms 17 adapted to detachably receive, in the

usual manner, a headlight conventionally shown at 18.

The shank 16 adjacent the upper end thereof is preferably rebent longitudinally and intermediate its ends is provided with a laterally projecting annular shoulder 19, the outer end of the shank being arranged to extend freely through the bore formed in the seat 14 with the shoulder 19 resting upon the seat 14 for supporting the bracket vertically, it being observed that the bracket 15 is thus mounted for turning movement upon the bracket arm 10.

Detachably secured to the lower end of the shank 16 is a head 20 which includes a preferably tubular cylindrical sleeve 21 having a medially arranged laterally projecting tubular sleeve 22 formed thereon, the sleeve 22 extending at substantially right angles 20 to the sleeve 21. The lower terminal of the shank 16 is removably received within the sleeve 21, the head 20 being connected with the shank by a suitable set screw 23 threaded into the wall of the sleeve 22 to engage 25 the shank.

A washer 24 is arranged to loosely surround the shank 11 to rest upon the adjacent upper end of the sleeve 22 and interposed between the said washer and the seat 14 30 is a preferably helical spring 25 which surrounds the shank; the spring 25 being adapted to normally hold the shoulder 19 yieldably in engagement with the seat 14 so that vertical movement of the body of the automobile under the influence of the springs 35 thereof, will not, under ordinary circumstances, effect a vertical shifting of the bracket 15 relative to the seat 14.

Detachably mounted upon the connecting rod 11 to extend laterally and forwardly therefrom, is an arm 26, the said arm being arranged in substantial alinement with the shank 16 and being suitably recessed upon one side and intermediate its ends, to receive the 45 connecting rod. Coacting with the arm 26 is a half bearing block 27 which is also suitably recessed upon one side to bear over the connecting rod and extending through the said block adjacent the ends thereof and 50 through the arm 26, are connecting bolts 28 adapted to clamp the block 27 against the arm 26 for rigidly securing the arm to the connecting rod.

At its outer extremity, the arm 26 is externally screw threaded to detachably receive one extremity of an internally screw threaded elbow 29, within the opposite extremity of which is screw threaded at one end, a vertically arranged upstanding arm 60 or tubular sleeve 30, the said sleeve 30 terminating at its upper end, in spaced relation laterally upon one side of and below the sleeve 21.

Freely connecting the sleeve 30 with the 65 sleeve 21 of the head 20 is a connecting mem-

ber 31 which is preferably formed from a single length of material substantially circular in cross-section and bent intermediate its ends to provide arms 32 and 33 which extend at substantially right angles to each other, the arms 32 being freely received within the sleeve 30, while the arm 33 is freely received within the sleeve 21 of the head 20, as best shown in Fig. 5 of the drawings, the arms being mounted for sliding movement within the said sleeves.

It is now to be noted that when the bracket 15 is moved vertically with the body of the automobile, under the influence of the springs thereof, that the arm 32 of the connecting member 31 will correspondingly slide freely within the sleeve 30 to compensate for such vertical movement. As will be readily understood, when the automobile is guided, in use, the connecting rod 11 will be reciprocated. Such reciprocation of the connecting rod will, through the medium of the arm 26 and elbow 29, correspondingly move the sleeve 30 laterally. When the sleeve 30 is thus moved, the said sleeve will turn around the arm 32 of the connecting member 31 about a vertical axis, while at the same time engaging the said arm to move it laterally with the sleeve. Such lateral movement of the arm 32 will cause the arm 33 to slide longitudinally within the sleeve 21 of the head 20, while at the same time engaging the sleeve to swing it about the axis of the shank 16. As will be clear, such swinging movement of the sleeve 21 will correspondingly rotate the said shank to direct the rays of the lamp 18 correspondingly as the connecting rod 11 is shifted to guide the automobile. It will therefore be seen that the arm 33 in the practical use of our improved headlight steering mechanism will slide within the sleeve 21 to compensate for the shifting movement of the connecting rod 11 either toward or away from the shank 16, while at the same time, the said arm will, through the medium of the sleeve 21, operate to effect the turning movement of the bracket.

Particular attention is now directed to the exceedingly simple construction which we provide. In any case where an automobile is equipped with the bracket arms 10, which, under ordinary circumstances rigidly support lamp brackets upon the seats 14, the said brackets may be removed and our improved mechanism quickly and easily applied. For this purpose, the head 20 is made detachable while it will be observed that, if necessary, the arm 26, the elbow 29, and the sleeve 30 may be also disconnected from each other.

Having thus described our invention, what we claim and desire to secure by Letters Patent is:—

1. A headlight operating mechanism adapted for operative connection to an ele- 130

- ment of a vehicle steering gear, said mechanism including a lamp receiving bracket, a head carried thereby and including a sleeve, a sleeve operatively connected to said element, and a member having free connection with said sleeves and operatively connecting the bracket with said element whereby shifting of the element will turn said bracket.
- 10 2. A headlight operating mechanism adapted for operative connection to an element of a vehicle steering gear, said mechanism including a lamp receiving bracket mounted for turning movement, a sleeve carried by said bracket and arranged in a plane at substantially right angles to the axis of the bracket, a sleeve operatively connected to said element and having its axis arranged at substantially right angles to the axis of said first mentioned sleeve, and a member slidably mounted in said sleeves and operatively connecting the bracket with said element whereby shifting of the element will turn the bracket.
- 15 3. A headlight operating mechanism adapted for operative connection to an element of a vehicle steering gear, said mechanism including a lamp receiving bracket mounted for turning movement, a head carried by said bracket and including a sleeve receiving the adjacent portion of the bracket, and a second sleeve, an arm rigidly connected to said element, a sleeve carried by said arm, and a member having arms one
- 20 slidably mounted within the sleeve carried by said first mentioned arm and the other slidably mounted within said second mentioned sleeve of the head, said member operatively connecting the arm with the bracket whereby shifting of the element will turn the bracket.
- 25 4. The combination with a vehicle having a bracket arm provided with a seat, of a headlight operating mechanism adapted for
- 30 operative connection to an element of the steering gear of the vehicle, said mechanism including a lamp receiving bracket having a shank extending freely through said seat and provided with a shoulder normally engaging the seat for supporting the bracket vertically, a head carried by said shank and

including a sleeve, a spring interposed between said head and the seat for normally holding the bracket against vertical shifting movement relative to the seat, an arm rigidly connected to said element, a sleeve carried by said arm, and a member having arms slidably mounted in said sleeves whereby shifting of the element will turn the bracket.

5. A headlight operating mechanism adapted for connection to an element of a vehicle steering gear, said mechanism including a lamp receiving bracket, an arm carried by the said element, and a member having angularly disposed arms, one mounted to turn about its longitudinal axis upon said first mentioned arm and the other freely connected to said bracket, whereby shifting of the element will turn the said bracket.

6. A headlight operating mechanism adapted for operative connection to an element of a vehicle steering gear, said mechanism including a lamp receiving bracket, an arm connected to said element, sleeves carried by the bracket and said arm respectively, and an element freely engaging in said sleeve for connecting the arm with the bracket, whereby shifting of the element will turn the bracket, said element being vertically shiftable in one of said sleeves and horizontally shiftable in the other of said sleeves.

7. The combination with a vehicle having a fender bracket, of a lamp bracket carried by said first mentioned bracket, an arm connected to an element of the vehicle steering gear, a vertically projecting sleeve carried by said arm, a sleeve carried by the lamp bracket and projecting laterally therefrom, and an element slidably mounted in said sleeves for connecting the arm with the bracket whereby shifting of the element will turn the lamp bracket.

In testimony whereof we affix our signatures in presence of two witnesses.
